BRACELET

Alpha H. Metcalf, Plainville, Mass., assignor to
 L. S. Peterson Company, North Attleboro,
 Mass., a co-partnership

Application March 13, 1946, Serial No. 654,019

1 Claim. (Cl. 63—7)

1

This invention relates to a bracelet, more particularly of the type having two tubular sections which are hinged together at their meeting ends while the other meeting ends may move into and from engagement and be detachably held by a clasp.

In the formation of a bracelet of this character, some sort of a clasp is provided which is soldered into the end of one of the sections and will clasp the other section to hold the sections in closed position.

One of the objects of this invention is to provide a catch which may be assembled with the bracelet without solder.

Another object of the invention is to provide a catch which may be easily removed by mechanical manipulation from the bracelet and replaced by a new catch.

Another object of this invention is to provide a catch for holding the bracelet in closed position and which will also limit the opening movement of the bracelet.

Another object of the invention is to provide a tongue which will hold the bracelet in closed position or limit the opening movement of the bracelet, and which may be inserted into the ends of the bracelet and held there without the use of solder.

With these and other objects in view, the invention consists of certain novel features of construction, as will be more fully described and particularly pointed out in the appended claim.

In the accompanying drawings:

Fig. 1 is an elevation showing the bracelet in closed position;

Fig. 2 is a view similar to Fig. 1 but showing the bracelet in open position;

Fig. 3 is a plan view on substantially lines 3—3 of Fig. 2;

Fig. 4 is a plan view partly in section on a larger scale and illustrating the tubular sections of the bracelet brought into abutting relation;

Fig. 5 is a view similar to Fig. 4 but showing the bracelet sections as spaced from each other and the relative position of the tongue member;

Fig. 6 is a perspective view of the tongue member.

In proceeding with this invention, I cut from sheet stock a strip of material which is slotted through a substantial part of its length to provide resiliency to a bar thus formed. On this bar, I provide projections which lock into openings in the bracelet to perform the functions of limiting the opening movement of the bracelet or to hold the bracelet in closed position. Cer-

2

tain of the projections may be removed from their respective openings by flexing the bar which carries them inwardly.

With reference to the drawings, I provide a bracelet section 10 and another bracelet section 11. These sections have their adjacent ends 12 and 13 hinged as at 14 so as to swing one relative to the other in any desired manner, thus permitting the free end portions 15 and 16 of the bracelet to be moved toward and from each other as shown in Figs. 1 and 2.

A tongue designated generally 17 is shown in perspective in Fig. 6 and consists of a piece of sheet stock cut out and arched so as to slide into the opposite tubular ends of the bracelet. This tongue 17 is slotted as at 18 throughout the major portion of its length providing bars 19 and 20 which may be flexed toward each other. A projection 21 is carried by one portion of the bar 20 while projections 22 and 23 are carried by other portions of the bar.

The bracelet section 11 has an opening 24 provided in its free end portion 16 and the projection 23 is positioned in this opening, as shown in Fig. 5, with its opposite right angular abutment surfaces 26 and 27 engaging the opposite edges of the opening 24 so as to prevent relative longitudinal movement of the tongue 17 in this end of the bracelet. Thus, this end of the tongue is designed to at all times move with the free end 16 of the bracelet.

The opposite end of the tongue 17 is positioned into the tubular end 15 of the bracelet and is of a size to slide thereinto with the opposite bars 19 and 20 engaging the inner surfaces of the tube. The projection 22 on the bar 20 will extend into an opening 28 in the end portion 15 of the section 10 as shown in Fig. 4 and will serve to hold the abutting end portions 15 and 16 of the bracelet in closed position. One edge 29 of this projection 22 is provided at right angles to the bar 20 so as to engage the edge of the opening 28 and prevent movement of the free ends of the sections from each other unless this projection 22 is disengaged from its opening. Such disengagement may occur by pressure upon the projection 23 inwardly as shown by the arrow 30 so as to cause such disengagement. The opposite edge of the projection 22 is inclined as shown at 31 so that when the tongue is in the position such as shown in Fig. 5 with its projection 22 out of the opening 28 and the sections are moved toward each other then this inclined surface 31 will bear against the edge of the open end of the tubular section 15 and cause the pro-

jection to be moved inwardly as the ends are brought together and this projection 22 will slide along the inner surface of the tubular bracelet until it reaches the opening 28 when it will snap into this opening and thus lock the sections together.

When the sections are being moved from closed position to open position and the tongue 17 is moving outwardly from the end portion 15 of the section 10, then the projection 21 which has a right angular abutment surface 32 will snap into the opening 28 when it reaches registry therewith such as shown in Fig. 5. The opposite edge 33 of this projection 21 is inclined so that when pressure is exerted on the tongue to move it into the end 15 of the section 10 this projection will be forced inwardly and will move over the inner surface of the tubular section 10 to the desired extent.

This tongue is entirely detachable from both ends of the sections by merely forcing inwardly to a sufficient extent the projections so that they will be free from the openings in which they engage when the same may be withdrawn and a new tongue may be positioned in the bracelet by reverse operation, all without the use of heat or solder.

A construction of this character is particularly advantageous in a baby's bracelet where destruction of the bracelet is liable to occur. Thus, these parts may be quickly and easily replaced for repair if necessary by the use of simple tools.

I claim:

A bracelet comprising two tubular sections hinged together at adjacent ends for the swinging of their free ends toward substantially abutting relation and away from each other, a tongue of a width equal to the width of the inside of the tubes with an open center providing spaced resilient arms connected at their ends, said tongue extending into the hollow free ends of said bracelet and slidably engaging the opposite side walls of the tubes and provided with three projections of the same piece of material as the tongue extending laterally from the same resilient arm and in generally the plane of both of said arms, the first of said projections being adjacent one end of

the arm and in a wall opening of the first tubular section with abutments on its opposite sides to prevent dislodgment from the opening by pressure in either direction longitudinally of the tongue and of a length to prevent dislodgment by inward flexure of said arm from which it extends and a second projection spaced a substantial distance from the first projection toward the other end of the arm in a position to enter an opening in the second tubular section and being provided with an abutment on the side toward the first projection and an inclined edge on the other side to cause it to be moved inwardly and withdraw it from its wall opening upon pressure tending to move said tongue into said bracelet section but to engage the edge of the opening and limit separating movement of the section ends, and a third projection located between the first two projections and spaced from the first projection substantially the distance that said wall openings are spaced when the free ends of the sections abut and positioned to extend into the opening in the second section upon movement of the sections to closed position, said third projection being closer to the first projection than to the second and releasable from the opening in the second section by pressure on the first projection and said third projection having an abutment on the side near the first projection to engage the edge of the wall opening in the second section and hold the sections closed, and an inclined edge on the other side to cause it to be moved inwardly by engagement with the end of the second tubular section.
